TURBODRIVE AND CONTROL

Hans O. Schjolin, Pontiac, Mich., assignor, by
mesne assignments, to General Motors Corporation,
Detroit, Mich., a corporation of Delaware

Original application February 9, 1938, Serial No.
189,596. Divided and this application February
9, 1939, Serial No. 255,497

22 Claims. (Cl. 74—189.5)

1

This is a divisional application of my U. S. S. N. 189,596, filed February 9, 1938, now matured as Letters Patent U. S. 2,272,434, issued February 10, 1942.

The invention relates to motor vehicles, and more particularly to an improved compact grouping of the driving mechanism for large, heavy vehicles such as buses, trucks and tractors.

In passenger buses in particular it is essential to arrange the drive mechanism in a space which shall detract the least from the pay load space, and while vehicles having transversely mounted power plants at the rear are known in the art, the present invention embodies a specific, improved arrangement, which, while including structures for the most part in general use and of conventional character, my arrangement imparts the drive to the vehicle wheels through a system which provides the least wastage of effort in power conversion from a transversely driving and torque converting assembly, in that the final output shaft receives its drive from the main centerline of the primary drive assembly.

A further novelty herein is the adaptation of the turbine form of torque-converter to the above noted form of drive, having least wastage of axial space consumed by the primary power group; the added utility of the assembly being especially adapted for fluid pressure actuation, the demonstration herewith showing a novel arrangement having means for rendering the drive effective or ineffective at will, through remotely operating connecting mechanisms, including fluid pressure devices.

The general arrangement of the units comprising the assembly of my invention is disclosed, and claimed with respect to the operation of clutch control means in my application noted above, of which the present application is a division, the claims herein being drawn to the overall transmission controls, as shall be apparent, further.

Further objects in the application of operator-operated interlocking controls for the above forms of driving mechanism are achieved herewith, in the prevention of wrong motion, and in the coordination of foot and hand operated elements, wherein the said interlocking means are connected with the aforesaid fluid pressure servo devices to accomplish the shifts of drive between direct and converter positions.

Additional objects and advantages will appear in the following detailed description when considered in connection with the accompanying drawings wherein—

2

Figure 1 is a schematic view of my invention, as applied to a motor vehicle such as a bus, wherein the power plant is arranged transversely at the rear.

5 Figure 2 is a longitudinal section of the primary power plant and driving assembly taken in a longitudinal plane of Figure 1.

Figure 3 shows the sectional detail of the form of one-way clutch utilized in the assembly of 10 Figure 2 on line 3—3, with shifter engaged.

Figure 4 is an enlarged view of the direct drive clutch D of Figure 2.

15 Figure 5 is an elevation-section view of a friction clutch used as a modification of the direct drive clutch of Figures 2 and 4, and identical in construction with the friction clutch C of Figure 2.

20 Figure 6 is an operation diagram, schematic insofar as the general arrangement of the control elements are concerned, but giving the operator's hand and foot operated controls in elevation and part section.

25 Figure 7 is a longitudinal section of the servo control valving of Figure 6.

25 Figure 8 describes in detail the interlocking arrangement of Figure 6 between the hand control and the pedal control, and is a view taken generally at 8—8 of Figure 6.

30 Referring particularly to Figure 1, it will be seen that my arrangement is shown as installed in the rear of a bus, with the primary power plant arranged transversely, and the output drive in the fore-and-aft plane of the vehicle, connecting by a short jackshaft to the conventional differential gear and axle drive to the rear wheels.

35 The primary power plant comprises an engine A of suitable type, a clutch C, a clutch D, a turbine type torque-converter T as a variable speed transmission, a gear assembly R, an overrunning device F, and an accessory drive mechanism E, all mutually coaxial.

40 The propeller shaft 60' extends forwardly with respect to the vehicle, and downwardly, from a point intermediate the engine A and the torque-converter unit T, connecting to the conventional differential gear, as noted.

45 In Figure 2 the engine crankshaft is shown at 1, mounted to rotate drive shaft 2 splined at 3 for slider 4, and splined at 5 for hub 6 and flange fitting 8.

50 Sleeve 9 mounted on bearings, surrounds shaft 2 and is attached to or integral with member 10, which has internal ring of teeth 11 and external bevel teeth 12.

The teeth 13 of slider 4 mesh with 11, whereupon member 10 is driven at engine speed.

Output jackshaft 60 rotating in bearings 61 in casing 20 is fixed to or integral with bevel gear 14 meshing with gear 12, transmitting the drive of sleeve 9 to the driving wheels of the vehicle, as shown in Figure 1.

Sleeve 15 concentric with sleeve 9 is bearing mounted on shaft 2 and has affixed gear 16 and roller clutch race 18, its inner end terminating in turbine element 30, which is the output member of the turbo torque-converter T. The outer roller clutch member 21 is externally splined at 22, and teeth 23 and spline 24 of sleeve 9 are aligned axially and radially therewith. Bridging slider 25 is splined internally at 21' so that when these teeth are in mesh with the teeth 23 of sleeve 9, the outer member 21 of the roller clutch assembly F is released. External teeth 26 of slider 25 are arranged to mesh also in the leftward position with the teeth 28 of gearbody 29 rotating in appropriate bearings in casing 20. Teeth 27 of gearbody 29 constantly mesh with reverse idler gear 32, which in turn mesh with gear 16. When slider 25 is in the right hand position of the figure, the drive from sleeve 15 is through roller clutch members 18 and 21 to slider 25, since internal splines 21' are then meshed with teeth 22 and thence from slider 25 to sleeve 9, yielding "forward" drive. When the slider 25 is in the left hand position, the drive is through gears 16-32, gearbody 29, slider 25 and sleeve 9 through the described toothed elements, yielding "reverse drive," which is obvious from the pairing of the gearing.

The hub 6 is one member of the turbine driving clutch C, and hub 33 is the other, splined on sleeve 34, integral with the input or impeller member 40 of the torque converter T.

The blades 50a and 50b are integral with reaction member 50 attached to, or integral with casing 20.

The rotation of impeller 40 causes the liquid contained in the casing to impinge on the blades 31a against which the liquid is thrown by centrifugal force from buckets 41 of the impeller 40. The specialized contour of the blades 50a and 50b permits the liquid to apply a rotational force to output-connected blades 31 and 31a mounted in rotor 30 attached to sleeve 15.

The multiplication of torque achieved in the turbine by virtue of the presence of the reaction members 50a and 50b is a well-known effect, described in U. S. 1,199,359 to Föttinger, filed June 19, 1906, issued September 26, 1916; and no invention is herein claimed for this characteristic. The present invention relates to the control arrangement for such a turbine type transmission wherein alternately operated clutches are actuated by fluid pressure servo means, remotely controlled.

It is deemed sufficient to state that the three elements of the turbine device, constitute a multiplier of torque imparting a variable speed to sleeve 15 from sleeve 34 rotating at engine speed.

When clutch C is engaged, the drive of the engine is transmitted to jackshaft 60 through the torque converter T at variable torques and speeds.

When clutch D is engaged, the drive is transmitted at a fixed ratio from engine shaft 1 to jackshaft 60; whereupon both members, input sleeve 34 and output sleeve 15, of the torque converter T may come to rest, since roller clutch F permits sleeve 9 to overrun sleeve 15.

The detail of roller clutch F is shown in Figure

3, and since this type of structure is well known, no lengthy description of its operation is believed necessary in the demonstration of my invention. It is worthy of note that the arrangement of the outer member 21, inner member 18, sleeve 15, and slider 25 constitutes a means for obtaining a full release of the roller clutch F when the slider 25 is placed in the "reverse" position. The arrangement permits the saving of power plant length by mounting the transfer control for forward, reverse and neutral drive between the toothed ends of the gearbody 29.

The inner face of the outer member 21 is smooth, and acts as a race for rollers 19 carried in cage 19a rotating with the inner one-way cam member 18. The rollers are biased by appropriate means, for one-way locking of members 18 and 21. The cage 19a has limited lost motion with respect to member 18.

The neutral position of the slider 25 occurs when the teeth 21' are demeshed from spline teeth 22' of element 21, partially meshed with teeth 23; but without mesh between teeth 26-28.

The detail of one form of clutch D is shown in Figure 4 where slider 4 splined at 3 to shaft 2 may mesh its teeth 13 with teeth 11 of bevel gearbody 10. Inside the overhang of teeth 11 is located friction ring 52, locked to rotate with member 19, and presenting tapered friction face 52a.

Balk piece 53 is splined at 54 to an extension of slider 4, for limited rotational motion with respect to slider 4. Auxiliary teeth 54a-55 cut on slider 4 are spaced to accommodate poppets 58, which are loaded radially by springs 59 in the radial recesses shown. The poppets 58 transmit axial force on slider 4 toward mesh of teeth 13-11, to the adjacent edge of spline teeth 54a of balk piece 53, so that registry of the teeth of 54-55 will coincide with release of drag force, permitting 13-11 to mesh without clash. Additional force is needed to depress the poppets for completion of mesh.

Piece 53, because of friction contact of its ring 56 with ring 52 at 52a, may then rock positively or negatively on the splines 54, so that teeth 54a of piece 53 will be out of registry with teeth 55, the teeth ends abutting, preventing further motion toward mesh of slider 4 and teeth 13.

If the faster member be the engine shaft 1 the balk piece 53 will rotate positively due to friction drag, to set up rejection of mesh. If output connected member 10 be the faster member, in either case there is rejection of mesh until the drag force acting on piece 53 disappears, as it does at synchronism, when the slider 4 may now move, teeth 55 may enter spline teeth 54a of piece 53, and also teeth 13 mesh with teeth 11, whereupon direct drive between shaft 1 and member 10 is accomplished.

During the asynchronous rotation interval of slider 4 and member 10, the opposing force condition persists, until synchronism is reached. Then the drag force from ring 52 to ring 56 disappears, which because of the release of the balked action, permit further free travel toward mesh, thereby allowing teeth 13-11 to complete meshing engagement.

This is described as a form of synchronism responsive mechanism having a balked, or rejection-of-mesh characteristic, wherein the friction and camming forces are provided to control the mesh motion rather than to absorb the differential inertias of the engine and vehicle. The characteristic may be described as a friction balked or lock-out action arranged to permit mesh or

reject mesh, according to synchronous or asynchronous rotations of the two members to be connected for unitary rotation.

It should be emphasized that if the driver allows engine speed to fall off below synchronism before the shifting force is exerted on the slider 4, the relative rocking action of balk piece 53 would be reversed, and the device would reject mesh because of the lag of teeth 55 with respect to teeth 54. The operator need therefore only bring the engine speed up to synchronism by depression of the accelerator pedal, whereupon, as before, the completion of mesh is permitted.

As will be seen, this form of synchronism responsive device is needed for clutch D to operate correctly in combination with the controls for the turbine torque converter.

The form of clutch C shown in Figure 2 is that of a single-plate friction clutch in which flange 6a of hub 6 terminates in drum 35 in which presser plate 36 is allowed limited longitudinal motion on splines 38. Disc spring 42 held by ring 39 to drum 35 extends inwardly toward hub 33 and may engage projection 37 of presser plate 36. The inner portion of spring 42 engages sleeve 45 movable longitudinally so as to shift the inner part of the spring 42 to either side of its critical flexion position with respect to the clamped outer edge.

When the sleeve 45 is positioned to the right, as in Figure 2, the external force applied to sleeve 45 shifts spring 42 through its critical flexure position, whereupon the force of the spring is exerted on projection 37, tending to load presser plate 36. Hub 33 carries the driven element 49 of clutch C to which the customary facing discs 48 are affixed. When plate 36 is loaded, clutch C transmits the drive of shaft 2 to the input member 40 of the torque converter T, at a given clutch capacity.

When the external force shifts sleeve 45 to the left, the spring 42 is anew flexed through the critical position, and its force is dissipated in holding the presser plate 36 free from load, thus disclutching clutch D.

It should be noted that the external force to be applied to sleeve 45 need only be effective to carry the spring 42 through the critical mid-position, and that no external force thereafter is needed to hold the clutch C engaged or disengaged.

External controls for clutches C and D, alternating their engagement, may therefore connect the drive for variable speed and torque through the converter unit T, or for fixed ratio or "direct" drive.

In Figure 5 the clutch assembly D takes the form of a friction clutch, identical in operation with that of the clutch just above described, and shown as connecting shaft 2 and sleeve 9. The prime-numbered elements of Figure 5 correspond to the parts described above in conjunction with the turbine driving clutch C of Figure 2.

Referring back to Figure 2, the collar of slider 4 is intersected by fork 70 affixed to rod 71 having sliding bearing in casing extensions 72 and 72a. Lock ring 73 retains biasing spring 74 which normally urges slider 4 toward engagement of teeth 13-11. Rocker lever 75 pivoted on the casing is arranged to load the slider 4 for disengagement through piston rod 76 and piston 126 of air cylinder 125 mounted on the casing 20 when air is admitted to pipe 122, to overcome the tension of return spring 77.

At the right of Figure 2, the casing 20 is shown broken away to disclose the external control applied to collar 44 which moves clutch sleeve 45

splined on casing extension 46. Fork 47 pivoted to the casing 20 is moved by its external lever 47a pivoted to piston rod 132 attached to piston 131 of cylinder 130 mounted on the casing 20. When air is admitted to pipe 123 and cylinder 130, collar 44 and sleeve 45 are moved toward the left. When air pressure is released therefrom, return spring 133 in cylinder 130 shifts collar 44 and sleeve 45 to the right. The servo actuation means are shown schematically, and may be so disposed in the engine compartment space as engineering requirements demand. The detail of the servo control system is given further in this specification.

The prime-numbered elements in the lower half of Figure 5 refer to identical parts in the control for clutch D of Figure 4, the arrangement for Figure 5 being identical with that for clutch C of Figure 2.

Figure 6 describes the remote control system for clutches C and D, whereby the operator may at will select and operate the drive through the torque converter, or in direct.

The driver controls consist of a gearshift lever assembly 100 mounted to rock longitudinally between three positions, forward, neutral and reverse; and pedal 101 having three operative positions; direct for actuation of clutch D, neutral, and the fully depressed position for putting in clutch C which drives the torque converter T.

The system of the invention herewith includes air servo means consisting of reservoir 102, maintained by the customary air pump 103 and automatic cut-off valve 104; air pressure feed pipes 105 and 106 connected to air main 108, valve assembly 110 controlling pressure to operate the control for clutch D; and valve assembly 120 controlling pressure to operate the control for clutch C, as shown in Figures 6 and 7.

The valve assemblies 110 and 120 are fitted to bores 111 and 112 respectively, in valve casing 109, and are operated by mechanism shown in detail in Figure 7, having external lever 115 and link 116 moved by lever 118 of pedal 101. When the pedal 101 is depressed to the "torque converter" position indicated, lever 118 swings clockwise from the position shown; and valve assemblies 110 and 120 admit atmosphere to lines 122-123 and to cylinders 125-130 in which pistons 126 and 131 slide. As will be seen later, the spring 133 of Figure 2 tends to engage clutch C, establishing drive through the converter T.

When pedal 101 returns to the "neutral" position shown, valve assembly 120 cuts off the atmosphere from line 123, and applies pressure to cylinder 130 so that clutch C is now disengaged, flexing spring 42 to the left side of its critical position.

Movement of the pedal 101 to the direct drive position rocks levers 118 and 115 counterclockwise, so that both valve assemblies 110 and 120 admit air pressure from line 108 to lines 122-123 and to cylinders 125-130. Piston 126 is arranged to permit spring 74 to load the slider 4 of Figure 2 toward engagement; or to shift the sleeve 45 of Figure 5 toward clutching engagement. Piston 131 maintains pressure on spring 133, but spring 42 being flexed to the left of its critical position is not thereby loaded.

When pedal 101 returns to the "neutral" position shown, valve assembly 110 cuts off the air pressure from line 105 and vents cylinder 125 and line 122 to atmosphere, so that clutch D may be disengaged, through the relieving of load on spring 74 in the instance of the jaw clutch slider

of Figure 1; or the action of spring 77', in the case of the modification of Figure 5.

The shifter lever member 90 is pivoted in fitting 91 fastened to the floor of the driver's compartment, and its extension lever 90a is pivoted to rod 92 extending to the rear of the vehicle, to bellcrank 93 mounted on the bulkhead 180. The other end of bellcrank 93 is pivoted to rod 94 movable parallel to the bulkhead; the rod 94 being in turn pivoted to rocking lever 95 pivoted on the casing 20 of the power plant. The opposite end of lever 95 projects into the casing 20 and is forked to operate the slider 25 of Figure 2.

Tracing out the motion, one will observe that the lever assembly 100 rocked counterclockwise exerts a pull on rod 92, rocking bellcrank 93 clockwise, and through rod 94, rocking lever 95 clockwise. The forked end of lever 95 then has shifted slider 25 of Figure 2 to reverse driving position. When the lever 100 is rocked clockwise, rod 92 receives a thrust, and bellcrank 93 and lever 95 rock counterclockwise; which, upon comparison with Figure 2, causes slider 25 to uncouple the reverse driving gearing 23-28-27-16, and reconnect sleeve 9 with member 21-25.

Since it is desirable that the operator be enabled to compel not only a neutral position of slider 25 but also a neutral drive for both clutches C and D, the lever 100 is of composite form, being normally held in an extended position from the pivot 96 of fitting 91, by spring 97 enclosed in sleeve 98.

The shifter lever rod 99 fits loosely in a recess of the lever 90, and projects through the pivot center 96 to the underside of the floorboard.

Bellcrank 80 pivoted at 81 is shaped at 82 to intersect the movement of the end 83 of rod 99.

The pedal 101 is mounted in pivot fitting 84-
floorboard, at 85.

A bridle or yoke 86 is arranged to slide in an aperture in the floorboard in a plane intersecting the "neutral" pedal position at right angles. Each leg of the yoke 86 is equipped with a roller 86a so that when the yoke 86 is pressed upward, the pedal 101 will be positioned at "neutral," whether it has been in direct or in the "torque converter" control positions.

Bellcrank 80 is linked to bellcrank 87 by the short rod 88, and 87 terminates in a cam foot 87a which intersects the motion of the rod end of yoke 86. Spring 89 bears against the floorboard fitting 84 and against cam foot 87a so that, normally, the pedal is free to move without interference by the bellcrank 87.

Whenever the driver depresses the knob 99a and rod 99 to compress spring 91, the above described bellcrank system becomes active, spring 89 is also stressed, so that unless the pedal 101 is already in the "neutral" position, the resulting clockwise rocking of the bellcranks 80 and 87 will shift the yoke 86 to neutral-compelling position.

It is realized, of course, that the previously described valve motions, in connection with the control movements of the pedal 101 will therefore ensue, when the shifter lever assembly 100 is manipulated as above described.

Figure 7 provides a sectional detail describing a specific form of valve mechanism used herewith as an example of the principles of the invention.

At the left the valve casing 109 is equipped with nipple 140 joined to pipe 105 leading from the pressure source. Dumbbell valve 141 held

by small spring 142 normally seals port 143 in casing 109.

In description of the valve assembly 110, bore 111 is occupied by valve body 145 having pivoted roller 146 at its right end. The valve 145 is centrally drilled at 148 and communicates with annular port 149 which may intersect atmospheric port 150 cut in casing 109. The hardened seat 152 is held on the spindle end of valve 145 by conical spring 151 which normally acts to cause valve 145 and roller 146 to follow cam 160.

Tapered seat 152 at valve 148 may be sealed by the adjacent end of the dumbbell valve 141 at full stroke.

Servo port 147 connects to line 122, and to cylinder 125 of the direct drive clutch D.

When the valve 145 is as shown in Figure 7, spring 151 is active, cam 160 is out of the way, air pressure in line 105 seals port 143 with dumbbell valve 141 assisted by spring 142, and the servo line 122 and cylinder 125 are vented through port 147, passage 148, port 149 and port 150.

When cam 160 stresses spring 151, shifting valve 145 to the left, port 149 is out of registry with port 150, and ground seat 152 intersects valve 141, unseating it, and admitting air pressure from line 105 and nipple 140 to port 147 and line 122. As has been noted, this position corresponds to the shift from "neutral" to "direct drive" of pedal 101, which through the linkage 118-116-115, rocks shaft 161 and cam 160 to move roller 146 and valve 145.

Similarly, in description of valve assembly 120, valve 155 in bore 112 of casing 109 is equipped with roller 156, has central port 158 communicating with port 159 and carries ground seat 162 held by conical spring 163. Dumbbell valve 164 is normally loaded by spring 165 to seal pressure port 166 connected to nipple 167 of line 123, and is unseated at full stroke of valve 155. Atmospheric port 168 in casing 109 may intersect port 159 of valve 155; and vent servo port 167, line 123 and cylinder 130 of the torque converter clutch C.

When the valve 155 is as shown in Figure 7, the cam 160 is active, spring 165 is compressed, ground seat 162 has intersected the dumbbell valve 164 sealing off the central passage 158, opening pressure porting 106 to the servo line 123, and the annular port 159 has shifted out of registry with the atmospheric port 168. In this position, the conditions correspond to the positioning of pedal 101 at "neutral drive."

The contouring of the cam 160 is such that when the clutch C is engaged, as when pedal 101 is in "torque converter" position, that is, fully depressed, both valve 145 and 155 are positioned for atmosphere to enter both cylinders 125 and 130; when it is in "neutral" position, valve 145 admits atmosphere to cylinder 125, but valve 155 admits reservoir pressure to cylinder 130; and when it is in the "direct drive" position, both valves 145 and 155 admit reservoir pressure to both cylinders 125 and 130.

In the case of the modification of Figure 5 where the jaw clutch of Figure 4 is replaced by the friction clutch for direct drive, the sleeve 45', which stresses spring 42', is arranged so that when servo pressure in cylinder 125 is exerted, the spring 42' is positioned to flexibly load projection 37' of pressure plate 36'. When the air pressure is relieved, spring 77' may overcome the force of 42' and disengage the clutch D.

When the operator is driving the vehicle in direct drive, the fluid pressure is therefore maintaining the sleeve 45' of the clutch D in engaged

position, and clutch C is disengaged. If there be a demand for acceleration at a lower speed ratio than 1 to 1, the operator will depress pedal 101 to "torque converter" position. Valve 145 first cuts off the servo pressure from cylinder 125, as the pedal 101 passes through "neutral" position; and spring 42 being shifted by spring 133, flexes away from the presser plate 36', and clutch D becomes disengaged.

When the pedal reaches the "torque converter" position, valve 155 moves to cut off servo pressure from cylinder 130, which vents to atmosphere, and spring 42 of clutch C is shifted so as to load the presser plate 36, and thereby establish drive through the clutch plate 48 and the torque converter T of Figure 2.

The relative biasing shown for the clutches for engagement and disengagement is believed to be novel, providing advantages in smooth operation, safety and the ability to maintain operation regardless of failure.

Further modification may be made of the relative action of the clutch control members with respect to the inherent characteristics of the disc spring actuating clutch controls, without departing from the scope of my invention.

In order to assure the shifter mechanism moved by the operator's control 99 from wrong motion, the shifter mechanism is interlocked, so that the ball 99a and rod 99 must be depressed for each shift among forward, neutral or reverse.

The sectional view of Figure 8 shows lever 90a, movable with the rocking shifter motion of rod 99 as shown by the arrows. On the inner face of lever 90a is welded guide key 170. Pad 82 of lever 80 moves in an arc to intersect key 170, and notches 171R, 171N, and 171F respectively, are the positions occupied by the tongue of the key 170 when the handlever assembly 100 is placed in the reverse, neutral and forward positions.

The lever assembly 100 cannot be rocked through these positions until gearshift ball 99a and rod 99 are depressed sufficiently to swing lever 80 and the notches of pad 82 clear of the key 170.

When the new shift is accomplished, the spring 89 returns the lever 80, pad 82 and notches to locking position. This simple interlock is believed an improvement over the customary poppet locking means.

The preceding description is believed to encompass a number of novel features, among which are the fluid pressure operated direct engine coupling of Figures 2 and 4, the related servo control motions of the shifter mechanism which alternates drive between clutches C and D, the novel arrangement of the friction clutch loading and unloading means in conjunction with the alternating fluid pressure control, and the free release mechanism involving the one-way clutch whereby the turbo-driven element may be brought to rest. The present divisional of my Letters Patent U. S. 2,272,434, noted above, is directed in particular to the features involved in the overall transmission controls of the invention as distinct from the clutch controls claimed in the parent case.

From the foregoing, it is apparent that a number of related novelties embodying invention in combination are herewith disclosed. Changes in the specific arrangements and forms of the structures may be made without departing from the spirit and scope of my invention, said invention being limited only by the scope of the appended claims.

Having thus described my invention, what I claim as new and desire to secure by Letters Patent is:

1. In a power transmission assembly, for motor vehicles in combination, a power shaft, a fluid turbine torque-multiplying transmission mounted to rotate concentrically with said shaft, a clutch device connecting said transmission with said shaft, operating means for said device, a power receiving shaft concentric with said power shaft, a gearing unit arranged to transmit reverse geared drive between said transmission and said power receiving shaft and to couple them directly, a load shaft arranged at right angles intersecting the centerline of said power shaft and said power receiving shaft, and a drive coupling consisting of a jaw clutch adapted to drive said power receiving shaft directly from said power shaft located adjacent the intersection of said centerline with said load shaft.

2. In power driven vehicles, adapted for transversely arranged power plants, in combination, a vehicle, an engine arranged transversely in said vehicle and connected to one end of a power shaft coaxial therewith, a hollow power receiving shaft surrounding a portion of said power shaft, a variable ratio drive comprising a fluid turbo-torque-multiplying transmission mounted coaxially with said shafts and adapted to transmit drive from said power shaft, a forward and reverse gear unit having an input element driven from the output of said transmission, a coaxial clutch device effective to couple said unit with the other end of said power shaft, whereby the drive of said power shaft is transmitted from the fluid transmission to said power receiving shaft, a load shaft adapted to drive the vehicle arranged in a plane intersecting the common centerline of said power shaft and said power receiving shaft, and a selective drive coupling effective to join said power shaft directly with said power receiving shaft when the drive of said clutch device is disconnected.

3. In a power transmission, in combination, a power shaft, a load shaft, a fluid transmission unit adapted to transmit drive between the shafts, a first clutch arranged to connect said shafts directly, a second clutch arranged to connect said shafts through said fluid unit, a gear unit adapted to transmit the drive of said fluid unit to said load shaft, a fluid operated piston adapted to actuate said first clutch, a fluid operated piston adapted to actuate said second clutch; a servo valve arranged to control said first-named clutch piston, a second servo valve arranged to control said second-named piston, a mechanism commonly operative upon both said valves embodying a cam, and a pedal connected to said mechanism effective upon said cam to establish sequential drive through one of said clutches, no-drive or drive through the second of said clutches, by opening of both of said valves, closing of one valve or by closing of both of said valves respectively.

4. In an automotive vehicle, in combination, a fluid torque converter, a clutch coupling to said converter, a power operated unit for establishing drive through said fluid torque converter which latter is arranged to connect a power and a load shaft, said unit comprising a piston adapted to disengage said clutch, an opposing spring adapted to engage said clutch, a gear unit adapted to transmit the drive of said converter and said clutch to said load shaft, a fluid servo valve effective to load or unload said piston according to positional movement, a pedal pivotally mounted on the floorboard of said vehicle for

controlling the action of said valve, intervening mechanism between said pedal and said valve movable at the will of the operator effective to set aside the action of said spring and cause said piston to disengage said clutch, and a ratio shift control for said gear unit operable upon said mechanism to establish a predetermined setting of said valve for given ratio positioning of said ratio shift control.

5. In a controlling mechanism for power plants, wherein a pneumatically operated clutch system affords direct drive, torque converter drive, or no drive, and wherein a forward and reverse driving gearbox is provided, operating in conjunction with a fluid torque converter device having direct drive means, a valve mechanism arranged to establish any of said drives or to establish no-drive by control of said means, a pedal controlling said mechanism movable into direct, converter or neutral drive positions, a hand lever adapted to shift the gears of said gearbox into forward, neutral or reverse, and interlocking means connecting said pedal and said lever whereby said pedal is moved to no-drive position before a shift of said lever through its neutral gear position from either forward or reverse positions may be made.

6. In vehicle power transmission controls, an engine shaft, an output shaft, gearing connected to said output shaft for selective forward neutral or reverse driving conditions, a clutch device one member of which consists of a flanged drum connected to said engine shaft, a movable presser plate rotating with said drum, and a discoidal spring adapted to exert spring force upon said plate; the other member of said device including a disc rotating with said intermediate shaft and arranged to be gripped between said plate and a portion of said drum; axially shiftable means for the inner circumference of said discoidal spring operative in one position to render said spring ineffective for releasing the drive of said device, a control pedal connected to said means having two positions in one of which the said means renders said spring ineffective to exert its force upon said plate, control mechanism connected to operate said pedal, a fluid torque converter having an input element connected to said disc and an output member connected to said gearing, and operator-operated means for shifting said gearing effective to control disengagement of said device by said first named means prior to predetermined gear shifting motion by said means in selecting and shifting said gearing through a connection to said mechanism enforcing the said pedal to move to a drive-releasing position upon a predetermined movement of said operator-operated means.

7. In vehicle power transmission controls, in combination, a fluid torque converter, a forward and reverse gear driven by said converter, a disconnectable driving clutch for said converter, a speed ratio selecting pedal adapted to control connection or disconnection of the drive through said clutch to said converter, a gearshift lever for said gear positionable to at least two gear drive positions, and having a supplementary clutch control motion, and interconnecting means between the said lever and said pedal operative to inhibit shift of said lever from either of said positions until said supplementary motion is obtained.

8. In vehicle power transmission controls, in combination, a direct coupling clutch connected to establish drive between input and output

shafts, a fluid torque converter, a second clutch adapted to establish indirect drive between said input shaft and said converter, gearing arranged in the driving path established by said second clutch, control means operative to actuate said clutches alternatively comprising pedal-operated mechanism, and a positionable control for said gearing coacting with said means and operative to disconnect both clutches prior to movement to or from at least two gear-drive-establishing positions.

9. In vehicle power transmission controls, in combination, a transmission drive assembly including a selective ratio gear unit and a clutch arranged to establish reduction drive between input and output shafts and through said unit, a second clutch arranged to establish direct drive between said shafts, a fluid torque converter included in the torque path of said first named clutch, a valve casing, two concentric bores in said casing, valve members mounted to slide in said bores, two fluid pressure chambers co-extensive with each of said bores, a fluid pressure source, two fluid pressure inlets connected to said source, each arranged to be connected with said chambers, auxiliary valves normally sealing said inlets from said chambers, clutch servo devices connected to said chambers operative to actuate said clutches for alternate engagement, fluid pressure relief porting in said casing intersecting the movement of said first named valve members, and mechanism for said two valve members operative to shift both for fluid pressure admission when in at least one position, and a connection between said gear unit control and said mechanism operative to condition the operation of said mechanism for given settings of said gear unit control.

10. In vehicle power transmission controls, in combination, a fluid torque converter drive including a power shaft adapted to be connected to an engine, a controllable coupling for connecting the shaft to the engine, a driven shaft concentric with said shaft, a one-way clutch having an internal member affixed to one of said shafts and an external member for connecting to the other of said shafts, a gear serving as the primary element of a reverse gear train connected to said first named shaft, a gear device connected to the other of said shafts adapted to couple to said external member, a reverse gear train engaging with said device and meshing with said first named gear, and positionable control mechanism for said device arranged to establish forward one-way drive between said shafts and through said torque converter to establish no-drive, or to couple the said shafts through the reverse gear train and said torque converter while releasing the said external member, according to the positioning of said mechanism.

11. In vehicle power transmission controls, in combination, an engine, a final drive, a torque converter, coupling means arranged to establish drive between said engine and said final drive including a gear compartment adjacent said converter housing, a reverse gear train therein comprising a primary gear affixed to an input shaft driven from said converter, a countershaft in said compartment having a plurality of longitudinally spaced idler gears one of which is caused to rotate by said primary gear, an output shaft extending into said compartment, splines on said output shaft carrying a slider therein having a range of motion limited by the longitudinal spacing of said idler gears, said slider having a ring

of teeth meshable with one of said idler gears, and having a second ring of teeth, a one-way clutch the inner member of which rotates with said input shaft, the outer member of which is externally toothed to mesh with said second ring of slider teeth, and control mechanism for said slider operative in successive positions to establish forward drive through said one-way clutch, establish no-drive or neutral, or to establish reverse drive through said primary gear, said countershaft, said first named ring of slider teeth, and said output shaft splines, according to successive positioning movements of said mechanism.

12. In vehicle power transmission controls, in combination, a variable speed fluid transmission providing infinitely variable reduction speed with torque multiplication through input, output and reaction turbine members, including a coupling clutch for establishing reduction drive by said transmission, a second clutch arranged to provide direct drive, a forward and reverse gearbox connected to transmit drive by one of said clutches, a manually positioned pedal arranged to establish drive by either of said clutches or to disengage both, a gearshift lever adapted to establish forward, neutral or reverse drive in said gearbox, and interconnecting means between said pedal and said lever operative to inhibit shifting of said lever from one position to another without restoration of said pedal to the position in which it enforces disengagement of both clutches.

13. In motor vehicle control devices, power and load shafts adapted to be coupled directly or indirectly at reduction ratio by a fluid turbine transmission unit, for both forward and reverse drive, a forward and reverse drive control means, a plurality of clutches, one of which is actuatable to couple said shafts directly and another of which is independently actuatable to couple said shafts indirectly through said unit, fluid pressure servo means operative to actuate said clutches alternatively in engagement and disengagement for coupling said shafts directly and in reduction ratio, valving controlling said servo means, mechanism for operating said valving, a pedal controlling said mechanism and having in its range of movement one position of control in which neither of said clutches is engaged, another position in which one of the clutches is engaged, and a third position in which the alternate clutch is engaged, and a coacting linkage between said drive control means and said pedal for co-ordinating their respective motions.

14. In motor vehicle power controls, an engine driving a power shaft, a load shaft, driving means arranged to couple said shafts for both forward and reverse drive embodying a fluid turbine transmission affording infinitely variable speed reduction ratios, alternately actuatable clutching means adapted to connect said shafts directly, or indirectly through said transmission; forward and reverse drive gearing coupling said transmission with said load shaft, a control for said gearing, fluid pressure operated servo means effective to cause no-drive, direct or reduction drive of said driving means by selective actuation of said clutching means, valving controlling the action of said fluid pressure operated servo means for selective actuation of said clutching means, mechanism for operating said valving, a pedal linked to said mechanism effective to establish no-drive or to establish alternate direct or re-

duction drive between said shafts through the actuation of said clutching means by said servo means as controlled by operation of said valving, and coacting control means between said gearing control and said mechanism for permitting or preventing action of the mechanism for predetermined control settings.

15. In motor vehicle drives, in combination, an engine, a power shaft driven by said engine, a load shaft, driving means arranged to couple said shafts embodying a fluid turbine transmission affording infinitely variable speed reduction ratios, and embodying forward and reverse gearing, alternately actuatable clutching means adapted to connect said shafts directly, or to connect said shafts indirectly through said transmission, fluid pressure actuation means effective to cause alternate direct or reduction drive by operation of said clutching means, valving controlling said fluid pressure actuation means, mechanism for operating said valving, a manual selection control for said forward and reverse gearing, and connecting means between said control and said mechanism effective to compel predetermined operation of said valving prior to selection by said control.

16. With a combination such as stated in claim 13, the sub-combination of an arrangement of the elements of said linkage effective to cause operation of said valving prior to predetermined forward or reverse shift selection of said gear.

17. In the combination of claim 14, the sub-combination of an arrangement of elements of said control means and said mechanism of said claim 14 operative for causing said valving to release both clutches for predetermined positioning of said gearing control.

18. In motor vehicle drive controls, a power transmission assembly including a power shaft driven directly by said engine, a load shaft, a first clutch arranged to couple said shafts directly when engaged, a variable ratio fluid transmission unit adapted to couple said shafts, a second clutch arranged to connect said power shaft to the input of said transmission, a gearing unit for coupling said load shaft to said fluid unit for transmitting the drive of said clutches, a control for said gearing unit, fluid pressure actuated means operative to cause alternate engagement and disengagement of said clutches, mechanism moved by said means for causing initial actuation of said first named clutch, while said means is disengaging said second named clutch, means associated with said first named clutch for preventing engagement thereof until said shafts are rotating at synchronous speeds and interlocking linkage controlling the action of said fluid pressure means in accordance with settings of said gear unit control.

19. In motor vehicle drives, an engine, a power shaft directly driven by said engine, a load shaft, a clutch arranged to couple said shafts directly, a variable speed fluid drive adapted to couple said shafts at infinitely variable reduction ratios, a shiftable gear unit, a second clutch arranged to connect said power shaft to said variable speed drive through said unit, a third clutch adapted to connect said load shaft with the output of said variable speed drive and said unit when said second clutch is engaged, blocking means in said first named clutch adapted to prevent its engagement at asynchronous speeds, loading means normally operative to bias said first named clutch for engagement, a member positionable to oppose the action of said loading means, fluid pressure

means including manually operated valving for actuating said first two named clutches and including a device for positioning said member, and a control for said unit combined with said control mechanism for said valving effective to establish alternate drive by said first and second named clutches or effective to compel both to remain disengaged at the will of the operator, as applied to the positioning of said mechanism.

20. In motor vehicle drives, in combination, concentric power and load shafts, a concentric fluid turbine transmission unit arranged to couple said shafts, a plurality of concentric clutching means adapted to couple said unit with said power shaft, to couple said shafts together directly, one of which couples said unit intermittently with said load shaft when said unit is coupled with said power shaft, a final drive shaft displaced at right angles to and intersecting the centerline of said power and load shafts, fixed ratio gear mechanism constantly coupling said load shaft and final drive shaft at a fixed reduction gear ratio, fixed ratio forward and reverse gearing including said intermittently operating clutching means displaced in the driving train between the output of said unit and the said load shaft, operative to set aside the action of said intermittent clutching means when said gearing is driving in reverse, and a control for said gearing effective to uncouple the said coupling means prior to shifting same to reverse.

21. In power plant installations for motor vehicles, in combination, an engine, a torque-multiplying torque converter, a load shaft, clutching means arranged to transmit the power of said engine directly to said load shaft while said torque converter is idling or non-rotating, and arranged to transmit the power of said engine to said load shaft at infinitely graduated variable speed ratios while said direct transmission of power therebetween is inhibited, a freewheel clutch adapted to disconnect the drive of said torque converter from said load shaft when said engine is directly cou-

pled thereto, a sliding toothed member to by-pass the drive of said freewheel clutch, a gear assembly surrounding said freewheel clutch, and effective to convert forward into backward rotation between the said torque converter when said member is made effective to by-pass said freewheel clutch; and arrangement of the said engine, the said clutching means, the said freewheel clutch, the said member, the said torque converter and the said load shaft wherein these named elements are all displaced concentrically, and a final drive shaft coupled to said load shaft by bevel gearing for driving the latter shaft always at a fixed ratio speed reduction from that of the said engine.

22. In power drive apparatus for motor vehicles, the combination of an engine shaft, a power output shaft, a transmission intermediate shaft, selective gearing for alternate coupling of said power output and said intermediate shafts positively for two-way forward or reverse drive; a clutch device having a member rotatable with said engine shaft and a mating member rotatable with said intermediate shaft, loading means normally effective to press said members together, an axially shiftable means for removing the effect of said loading means so as to disengage said clutch device, control mechanism for said axially shiftable means; a fluid turbine torque converter having an input element connected to said intermediate shaft and an output element connected to drive said power output shaft, and operator-operated means for shifting said selective gearing for alternately coupling said power output and said intermediate shafts for said two-way forward or reverse drive, said last named means being connected to said control mechanism for effecting disengagement of said device during operator-operated motion of said last named means predetermined for a subsequent alternation of drive by said selective gearing.

HANS O. SCHJOLIN.
